(57) **CLAIM**

The ornamental design for a jig for positioning rods, as shown and described.

DESCRIPTION

FIG. 1 is a perspective view of a jig for positioning rods showing my new design;

FIG. 2 is a front view thereof, a rear view being an identical image of the front view;

FIG. 3 is a left side view thereof, a right side view being an identical image of the left side view;

FIG. 4 is a top plan view thereof;

FIG. 5 is bottom plan view thereof;

FIG. 6 is a sectional view taken along line 6-6 in FIG. 4;

FIG. 7 is a sectional view taken along line 7-7 in FIG. 4; and, FIG. 8 is a referential perspective view showing the article placed in a hollow pole such as a utility pole (not shown) with the rods for reinforcing the hollow pole.

The broken lines showing on the drawing disclosure are for illustrative purposes only and form no part of the claimed design.
